UNITED STATES PATENT OFFICE.

OLIVER PERRY ANDERSON, OF NASHVILLE, TENNESSEE.

DETACHABLE TYPE.

1,206,972.

Specification of Letters Patent.

Patented Dec. 5, 1916.

Application filed March 30, 1916. Serial No. 87,779.

To all whom it may concern:

Be it known that I, OLIVER PERRY ANDERSON, a citizen of the United States, residing at Nashville, in the county of Davidson and State of Tennessee, have invented certain new and useful Improvements in Detachable Type; and I do hereby declare the following to be a full, clear, and exact description of the invention, such as will enable others skilled in the art to which it appertains to make and use the same.

My invention relates to new and useful improvements in detachable type and particularly to that class used in connection with typewriters, adding machines, and the like, and my object is to provide an extra type adapted to be quickly connected with the type bar of the machine. And a further object is to provide means for holding the type in position until such time as it is desired to remove or change the same.

Other objects and advantages will be hereinafter set forth and more particularly pointed out in the accompanying specification.

In the accompanying drawings which are made a part of this application, Figure 1 is a detail elevation of a type bar, showing my detachable type applied thereto. Fig. 2 is a similar view, showing the detachable type and securing means in section. Fig. 3 is an end elevation of the type bar and detachable type. Fig. 4 is a similar view, showing the manner of releasing the detachable type. Fig. 5 is an elevation partly in section of a different form of type bar, and Fig. 6 is a similar view of a still different form of detachable type and fastening means.

Referring to the drawings in which similar reference numerals designate corresponding parts throughout the several views, 1 indicates the type bar which may be constructed in the usual or any preferred manner and 2 indicates the type shank, 3 the usual form of head for the type shank and 4 indicates the type secured to the type head.

In order to quickly change the character of the type I provide a housing 5, the lower edge of which is open to receive the head 3, said housing having type 6 attached thereto and positioned over the regular type 4 and coöperating with the platen of the machine the same as the regular type. In order to hold the casing firmly in engagement with

the head 3, the angle-shape spring 7 is provided, the vertical portion of the spring being secured to one end section of the housing by means of a rivet 8, the horizontal portion of the spring 7 extending below the head 3 and impinging thereagainst, and to increase the locking action of the spring with the head, a recess 9 is formed in the lower face of the head 3 with which coöperates a projection 10 formed by striking up a portion of the horizontal end of the spring. In attaching or removing this form of housing, the horizontal portion of the spring 7 is swung laterally out of the path of the head 3 so that the housing can be readily removed from or introduced over the head portion of the spring. After the housing is properly positioned over the head 3, the horizontal portion of the spring is forced below the head and the projection 10 snapped into engagement with the recess 9, thereby securely holding the type in engagement with the head, until such time as it is desired to remove the same.

In Fig. 5 of the drawings, the housing 5 is shown attached to a different form of type bar 11, in that the type 12 is attached directly to the type bar, the housing being attached to this form of type bar the same as in Figs. 1 and 2.

In Fig. 6 of the drawings, I have shown a different form of housing, in that one end wall thereof is dispensed with, so that the housing 13 can be slipped endwise over the head 14, and in this instance, the horizontal portion of the spring 15 passes below the head 14 without swinging movement thereof and the projection thereon engages the recess in the lower face of the head. In this construction, the usual form of type shank and head is removed from the type bar and the head 14 substituted therefor, the ordinary type carried by the head being omitted. When a head of this class is used and the form of type is to be changed, it requires the introduction of a different housing over the head each time the type is changed. It will also be understood that when type bars having the type secured directly thereon are encountered, in which difficulty is experienced in attaching the housing, a special form of type bar is to be substituted therefor and so arranged as to readily receive the special form of detachable type.

Having thus fully described my invention

what I claim as new and desire to secure by Letters Patent of the United States, is:—

1. The combination with a type bar and the type carrying head thereon, of a housing having type thereon, and an angle shaped spring pivoted to the housing having a projection thereon adapted to interlock with the type carrying head.
2. The combination with a type bar and a head therefor, having a recess, of a housing having type attached thereto, and an angle shaped spring having a projection adapted to enter said recess and secure the housing to said head.
3. The combination with a type bar and

a head therefor, having a recess, of a housing having type attached thereto, and an angle shaped spring pivotally secured to the end of the housing and adapted to swing laterally thereon, said spring having a projection adapted to enter said recess and secure the housing to said head. 20

In testimony whereof I have signed my name to this specification in the presence of two subscribing witnesses.

OLIVER PERRY ANDERSON.
